UNITED STATES PATENT OFFICE.

WILLIAM S. MONROE, OF CHICAGO, ILLINOIS.

POWER-GENERATING SYSTEM HAVING AIR HEATER.

Application filed March 10, 1923. Serial No. 624,080.

My present invention relates to systems for generating power in which steam from steam generators is supplied to a multi-stage prime mover and in which some of the exhaust 5 from one or more stages of such prime mover is withdrawn from the prime mover and the heat thereof returned to the system.

My present invention will be best understood from the following description and 10 the annexed drawing in which I have shown diagrammatically one embodiment.

In this illustrative embodiment, 10 is a steam boiler having a forced-blast stoker 11 and a superheater 12 from which steam 15 is supplied through a pipe 13 to the high-pressure stage of a multi-stage steam turbine 14 connected to a generator 15. The boiler is provided with an economizer 16 over which the gases flow downward from the 20 boiler 10, and from thence to the stack 17.

The condenser 18 receives the exhaust from the turbine 14 and the condensate passes through the pipe 19 into a feed-water and air-heating system to be described more 25 fully hereinafter, the pump 20 forcing this condensate into the system, and a feed pump 21 withdrawing the feed water from the system and forcing it through the pipe 22 into the economizer 16 from which it passes into 30 the boiler 10 in the usual manner.

The system referred to comprises the heaters 23, 24 and 25, the heater 23 being supplied through the pipe 26 with steam from between a pair of relatively low-pressure 35 stages of the turbine, the heater 24 being supplied through the pipe 27 with steam from between a pair of stages at a relatively higher pressure, and the heater 25 being supplied through the pipe 28 with steam from 40 the steam packing gland of the turbine. These heaters 23, 24 and 25 are connected by pipes 29, 30 and 31 with the condensate pump 20 and with each other, so that these 45 heaters are in series in the direction of flow of the water therethrough, the pipe 32 connecting the last heater with the feed pump 21.

A duct 33 connected to a forced-draft fan 34 supplies air to the fuel on the grate 11. 50 This air passes over heating surfaces in an air heater 35, these heating surfaces being supplied with hot water from the heater 25 through a pipe 36, the water after passing through the air heater, returning 55 through a pipe 37 to a pump 38 which is connected to the pipe 29.

By way of illustration, but without intending to be limited to the specific arrangement or figures, the operation of my system may be described as follows:

The steam passing through the pipe 26 may have a temperature of, say, 150° F. The condensate, therefore, will first be heated to approximately that temperature and will then flow to the second heater 24, 60 where it will be heated by steam at a temperature of, say, 200° F. From the heater 24, it will flow to the heater 25, where it is heated by steam which may have a temperature of, say, 212°. From the heater 25, 65 sufficient water will be drawn by the pump 21 to feed the boiler. The pump 38 acting with the pump 20, will cause the remaining water in the system to circulate through the air heater 35 to heat the air passing to 70 the grate 11. It will thus be seen that the steam drawn from the intermediate stages of the turbine will be utilized not only to heat the feed water to the desired temperature, but will also heat the combustion air 75 and that the quantity of steam which may thus be drawn off from the turbine is not limited to the amount required to heat the feed water to the desired temperature. Indeed, it will be noted that the system including the heaters 23, 24, 25, air heater 35 80 and the circulating pump 38, constitute what is, in effect, a closed system so far as the air heater is concerned, in which the circulating water serves to transfer the heat from 85 the steam withdrawn from the turbine to the combustion air, though I find it advantageous to use this system also to heat the feed water in the manner which I have 90 described.

While I have shown three heaters supplied with steam from the turbine, it will be understood that any number may be used though I find it advantageous to use a plurality in the manner illustrated, in order that 100 the temperature of the water may be increased progressively as it flows through the several heaters. Preferably, the air heater will be of such size that though it receives water, say, at a temperature of 212° F. from 105 the heater 25, the water passing therefrom will be reduced to a temperature of, say, from 60 to 80° F. or approximately that of the condensate from the condenser 18.

It will be understood that the arrangement 110 which I have used for purposes of illustration may be widely varied and that I do not

wish to be limited to the specific form which I have shown.

I claim:

1. In a power-generating system, a steam boiler having a furnace, a multi-stage prime mover supplied with steam from said boiler, an air heater arranged to transfer heat from water to air, means to pass combustion air through said air heater to the furnace, a water-circulating system connected to said air heater and having a heat-exchanger therein, connections to supply steam from an intermediate stage of the prime mover to said heat-exchanger and a pump in said water-circulating system, whereby the water may be circulated through the air heater and the heat exchanger at any desired rate.

2. In a power-generating system, a steam boiler having a furnace, a multi-stage prime mover supplied with steam from said boiler, an air heater arranged to transfer heat from water to air, means to pass combustion air through said air heater to the furnace, a water-circulating system connected to said air heater and having a heat-exchanger therein, connections to supply steam from an intermediate stage of the prime mover to said heat-exchanger, and connections between said water-circulating system and said boiler to supply feed water from the system to the boiler.

3. In a power-generating system, a steam boiler having a furnace, a multi-stage prime mover supplied with steam from said boiler, an air heater arranged to transfer heat from water to air, means to pass combustion air through said air heater to the furnace, a water-circulating system connected to said air heater and having a plurality of heaters therein, a connection between each heater in the water circulating system and the exhaust outlet from an intermediate stage of the prime mover arranged to supply steam at progressively higher temperatures to the

water which flows to the air heater and a pump in said water-circulating system, whereby the water may be circulated through the air heater and the heaters at any desired rate.

4. In a power-generating system, a steam boiler having a furnace, a multi-stage prime mover supplied with steam from said boiler, an air heater arranged to transfer heat from water to air, means to pass combustion air through said air heater to the furnace, a water-circulating system connected to said air heater and having a plurality of heaters therein, a connection between each heater in the water circulating system and a pair of intermediate stages of the prime mover arranged to supply steam at progressively higher temperatures to the water as it flows toward the air heater, and a connection between the last heater and the boiler to supply feed water to the boiler.

5. In a power-generating system, a steam boiler having a furnace, a multi-stage prime mover supplied with steam from said boiler and having a condenser for the exhaust steam therefrom, an air heater arranged to transfer heat from water to air, means to pass combustion air through said air heater to the furnace, a water-circulating system connected to said air heater and having a heater therein, connections to supply steam from an intermediate stage of the prime mover to said water heater, a connection and a pump between the exhaust steam condenser and said water-circulating system, and a connection and a pump between the water-circulating system and the boiler, said water-circulating system having a pump therein, whereby the water in the system may be circulated through the heater and the air heater at any desired rate, independently of the supply of condensate or the amount of feed water required by the boiler.

WM. S. MONROE.
